UNITED STATES PATENT OFFICE.

HARRY FEDER, OF NEW YORK, N. Y.

DESIGN FOR SKIRT-BINDING.

SPECIFICATION forming part of Design No. 29,557, dated October 25, 1898.

Application filed September 26, 1898. Serial No. 691,942. Term of patent 14 years.

To all whom it may concern:

Be it known that I, HARRY FEDER, a citizen of the United States, and a resident of New York, in the county and State of New York, have invented and produced a new and original Design for Skirt-Binding, of which the following is a specification, reference being had to the accompanying drawings, forming a part thereof.

The leading features of my design consist in a skirt-binding presenting on each of its two opposite sides a brush-like edge, a plain band, and a mottled band intermediate of the brush-like edge and plain fabric, and in a transverse section presenting a brush-like edge, a thin head, and bands offset from the opposite sides of the thin head intermediate of the brush edge and the thin portion of the head.

In the accompanying drawings, Figure 1 is a view of the binding in front elevation. Fig. 2 is a view in rear elevation, and Fig. 3 is a transverse section.

A represents the plain band along the head portion, B the brush-like edge, and C the mottled band intermediate of the brush-like edge and plain portion of the head.

What I claim is—

The design for skirt-binding, substantially as herein shown and described.

In testimony that I claim the foregoing as my invention I have signed my name, in presence of two witnesses, this 24th day of September, 1898.

HARRY FEDER.

Witnesses:

FREDK. HAYNES,
EDWARD VIESER.
